CADDY CAR SEAT

Alan E. Koplar and Ignacio R. Quiroz, Chicago, Ill.

Application March 5, 1956, Serial No. 40,462

Term of patent 3½ years

(Cl. D14—6)

Fig. 1 is a perspective view of a caddy car seat showing our new design;

Fig. 2 is a top plan view of said seat; and

Fig. 3 is a side elevation of said seat.

We claim:

The ornamental design for a caddy car seat, as shown.
